United States Patent Office

Des. 219,632
Patented Dec. 29, 1970

219,632

HANDBAG

Gladys I. Spear, 205 Allen St., New York, N.Y. 10002

Filed Mar. 4, 1970, Ser. No. 21,744

Term of patent 14 years

Int. Cl. D3—02

U.S. Cl. D87—3

Fig. 1.

Fig. 2.

FIG. 1 is a bottom rear perspective view of a handbag showing my new design wherein the lower edge is decorated with studs;

FIG. 2 is a top front perspective view of the design of FIG. 1;

FIG. 3 is a bottom rear perspective view of the design of FIG. 1 wherein the lower edge is decorated with stitches; and

FIG. 4 is a top front perspective view of the design of FIG. 3.

I claim:

The ornamental design for a handbag, as shown and described.
